US00D682519S

(12) **United States Design Patent**
Litchfield et al.

(10) **Patent No.:** **US D682,519 S**
(45) **Date of Patent:** **** May 21, 2013**

(54) **SHOE SOLE**

(75) Inventors: **Paul E. Litchfield**, Westboro, MA (US); **William McInnis**, Westwood, MA (US); **William Marvin**, Canton, MA (US); **Kevin Leary**, Dedham, MA (US); **Paul Shinney**, Milton, MA (US)

(73) Assignee: **Reebok International Limited**, London (GB)

(**) Term: **14 Years**

(21) Appl. No.: **29/383,134**

(22) Filed: **Jan. 12, 2011**

(51) **LOC (9) Cl.** 02-04
(52) **U.S. Cl.**

USPC **D2/955**; D2/951; D2/956; D2/957

(57) **CLAIM**

The ornamental design for a shoe sole, as shown and described.

DESCRIPTION

FIG. 1 is a bottom perspective view of a shoe sole showing our new design;

FIG. 2 is a bottom plan view thereof;

FIG. 3 is a side view thereof;

FIG. 4 is another side view thereof;

FIG. 5 is a rear view thereof; and,

FIG. 6 is a front view thereof.

The broken lines in the Figures show environment for illustrative purposes only and form no part of the claimed design.

1 Claim, 5 Drawing Sheets
